Inventor
David H. Wilson,

UNITED STATES PATENT OFFICE.

DAVID H. WILSON, OF PHILADELPHIA, PENNSYLVANIA.

DIAPHRAGM-FRAME MOUNTING FOR REPRODUCERS.

1,425,566.

Specification of Letters Patent. Patented Aug. 15, 1922.

Application filed September 15, 1921. Serial No. 500,883.

To all whom it may concern:

Be it known that I, DAVID HENRY WILSON, a citizen of the United States of America, residing at 6069 Chester Avenue, Philadelphia, in the county of Philadelphia and State of Pennsylvania, have invented certain new and useful Improvements in Diaphragm-Frame Mountings for Reproducers, of which the following is a specification.

10 This invention relates to phonographs and other like sound reproducing machines.

More particularly the invention relates to diaphragm frame mounting for reproducers.

15 One important object of the invention is to improve and simplify the general construction of devices of this character.

A second important object of the invention is to provide an improved mounting 20 for a diaphragm frame which will afford the frame absolute freedom of motion and vibration.

A third important object of the invention 25 is to provide an improved and simple means for regulating the extent of movement and vibration in the diaphragm frame mounting of such reproducers.

With the above and other objects in view, the invention consists in general of certain 30 novel details of construction and combinations of parts hereinafter fully described, illustrated in the accompanying drawings, and specifically claimed.

In the accompanying drawings, like characters of reference indicate like parts in the several views, and:—

Figure 1 is a face view of a reproducer constructed in accordance with this invention.

40 Figure 2 is a view similar to Figure 1 but with the front ring of the casing removed.

Figure 3 is a section on the line 3—3 of Figure 1.

45 Figure 4 is an enlarged detailed section through the line 4—4 of Figure 3.

Figure 5 is an enlarged detailed section on the line 5—5 of Figure 3.

50 Figure 6 is a detailed section on the line 6—6 of Figure 4.

In carrying out the objects of this invention and in the embodiment shown in the accompanying drawings there is provided a casing having a back 10 surrounded by an 55 annular wall 11 projecting toward the front of the reproducer. In the centre of the back

wall is a circular opening 12 and at the top of the reproducer is a boss 13 threaded interiorly. The diaphragm case proper consists of a back 15 surrounded by an annular 60 wall 16 and having a centrally located rearwardly projecting tube 17, which passes through the opening 12 and is free therefrom. The front edge of the wall 16 is threaded interiorly for the reception of a 65 retaining ring 18 and between this retaining ring and the back wall is located the usual diaphragm 19 which is supported around its periphery by the elastic rings 20 of rubber or other like material. At the 70 front of the reproducing casing is a retaining ring 21 which is secured to the back of said casing by screws 22 entering lugs 23 formed on the wall 11. The proportions of the diaphragm and the reproducer casing 75 are such that a channel 34 surrounds the frame and said frame is spaced both from the back 10 and the retaining ring 21 as clearly shown in Figure 3.

Surrounding the frame is a groove 25 and 80 between the wall 11 and the wall 16 are mounted balls 26 which rest in this groove. Projecting inwardly from the wall 11 are lugs 27 against which two of the balls 26 rest. Through the boss 13 extends an adjusting screw 28 having recess 29 in its point and between this recess and the wall 16 is mounted the third ball 26, the parts being so arranged that the three balls are evenly spaced around the diaphragm frame. 90 The screw 28 is projected with a knurled edge 30 for adjustment and there is also on this screw a lock nut 31 to hold the screw in its adjusted position.

Mounted on the casing is the usual needle-bar support 32 carrying the needle-bar 33 the interior end of which is connected to the diaphragm and the outer end of which is provided with the ordinary needle holder 34. 100

It will be obvious, from the construction, that the diaphragm frame is supported within the casing by a three-point suspension and that, by adjusting the screw 28 the pressure on the balls may be regulated 105 at will so that the support between the casing and the frame may be made as loose or as rigid as desired.

There has thus been provided a simple and efficient device of the kind described 110 and for the purpose specified.

It is obvious that minor changes may be

made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

- 10 1. In a device of the kind described, a reproducer casing, a diaphragm frame positioned within said casing in spaced relation to the walls thereof, balls spaced evenly around the periphery of the frame between said frame and the casing, and means to exert pressure inwardly on one of said balls and thereby increase the pressure between the remaining balls and the frame.

2. In a device of the kind described, a reproducer casing having a back wall and a 20 peripheral side wall, a diaphragm frame having a back wall and a side wall mounted within the casing and spaced from the back and side walls of the casing, the side walls of said frame having a peripheral groove, 25 a triad of balls held in said groove between the frame and the side wall of the casing, lugs supporting two of said balls, and a screw extending through the side wall of the casing and bearing on the remaining 30 ball, said lugs and screws being positioned to hold the balls in evenly spaced relation.

In testimony whereof I hereunto affix my signature.

DAVID H. WILSON.
